JEAN F. WOLFS, OF NEWARK, NEW JERSEY.

OIL CUP.

Application filed August 19, 1920. Serial No. 404,644.

To all whom it may concern:

Be it known that I, JEAN F. WOLFS, a citizen of the United States, and a resident of Newark, county of Essex, and State of New Jersey, have invented certain new and useful Improvements in Oil Cups, of which the following is a specification.

This invention relates to an improved oil cup which is particularly adapted for use on elements that are jostled or vibrated, such as the shackles of steering gears or on the eye bolts of leaf springs on automobiles, and which cup does not feed oil when the parts are at rest, but begins to feed as soon as the parts are in use and agitated.

The oiler is designed so that the inner end of the outlet tube of the oiler is above the level of the oil and the inner walls are disposed so that when the oil in the cup is splashed its general movement is in the direction of the inner end of the outlet tube.

The invention is also designed to provide an oiler in which the filling is limited, due to the construction, so that an air chamber is formed above the normal level of the oil, the inlet end of the outlet tube being located in the air chamber.

Another element of the invention is the provision of a wick, which wick is so constituted that it does not permit of an air check to the extent of interfering with the slow feeding of oil, and which positively carries a small quantity of oil from the cup or container when the inner end of the wick, which projects from the inner end of the outlet tube, is supplied with oil. The wick is also advantageous in that small quantities of dirt, which, if they accumulate, form a stoppage, do not lodge in the wick.

The invention is illustrated in the accompanying drawing, in which Figure 1 is a section with the lower part in elevation, showing one form of oiler embodying my invention. Figure 2 is a section, looking upward, taken on line 2 in Figure 1. Figure 3 is a section of a modified form, and Figures 4, 5 and 6 are sections of the upper portion of several oilers of a still further modified construction.

The oil cup comprises a main portion or container 10 which, in Figures 1 and 2, comprises a dome-shaped member 11 and a flat end piece 12, which are usually secured together by any usual means, preferably brazing, and as this form is designed to pro-

vide for a horizontal feeding of oil the end piece 12 is provided with a hub 13 which is usually screw-threaded so that it can be attached to a shackle or any other portion of a mechanism which is adapted to be lubricated.

The top of the casing is provided with a filling tube 14 which is suitably secured to the casing and extends inwardly from the top to the desired extent, and is provided with a suitable closure, such as the plug 15, which, in the form shown, screws down into the filling tube 14, and in order to make a tight joint I usually provide the plug with a washer 16.

An outlet tube 17 is arranged in the container and has its outer open end 18 disposed so as to conduct oil to the part to be lubricated, the inner or inlet end 19 of the tube 17 being preferably bent over so that its open end faces downward and is located within an air chamber 20, which air chamber is established when the container is filled, as the wick, to be hereinafter more fully described, is situated in the outlet tube and prevents the escape of air to an extent or at a speed that causes the bottom end of the filling tube to define the normal level of the oil when the cup is filled, since the cup will over-flow before the air chamber 20, that is, the part of the container above the bottom of the filling tube 14, can receive a material amount of oil.

A wick 21 is arranged in the tube 17, this wick being made of strands of fine wire, the strands of wire being wound loosely, but the wick itself being of a diameter to substantially fit the tube 17. This wick will maintain its shape to an extent to permit its inner and projecting end 22 being formed into a loop, which is preferably around the filling tube 14 so as to provide a material length of wick to receive oil. The material itself of which the wick is composed is not absorbent, but being gathered loosely in a wick sheds the major portion of oil that is deposited on it, but the film of oil that is established around the wires, and the small drops that lodge in between the strands, are conducted by capillary attraction along the wick and through the outlet tube to the part to be lubricated.

The member 11 with its curved or semi-arched top directs oil that is splashed upward toward the wick and oil is thus thrown

up and over the wick when the container is shaken or agitated, as it would be, for instance, on an automobile when the automobile is in motion.

5 In Figure 3 is shown another form in which the container is adapted to be placed on top of the element to be lubricated; in other words, the feed is downward. The casting 23 is substantially spherical and is provided with a suitable head 24 by means of which it is secured in place, the converging inner walls cooperating with the filling tube 25 to form the air chamber 26. The filling tube is closed by a suitable plug 27 and the inner end 28 of the outlet tube 29 is preferably turned over so that its open end faces downward and oil is not directly deposited into the outlet tube. The outlet end 30 of the outlet tube projects out to the hub 23 and, being a fine tube, is usually strengthened by securely fastening it to the outer end of the hub, if desired, this being in the form of a deposit of solder 31.

The wick 21 is arranged in the outlet tube 29, and the loop 22 thereof, in the form shown, is curled so that it bears against the outside of the filling tube and thus receives not only oil that is splashed on it, but oil that is splashed against the filling tube.

30 In Figure 4 I show a modified form, the container 23 having the filling tube 32 provided with a gutter 33 extending around the outside of it at the bottom, the outlet tube 34 being connected at one point with the gutter 33, and the loop 22 of the wick 21 lying in said gutter to transmit from said gutter to the outside of the oiler oil deposited in the gutter when the container is agitated.

40 In Figure 5 I show a construction somewhat similar to Figure 4, in which the filling tube 35 enters the gutter from the top instead of the bottom, and in Figure 6 I show a still further modification in which the outlet tube 36 is shown, this tube entering the side of the gutter and extending down in said gutter nearly to the bottom thereof so as to syphon from said gutter, oil that is lodged therein, as will be readily understood.

These different forms are used according to various circumstances, such as the weight of the oil and also bearing requirements, and therefore I use various sizes of tubes, 55 and various sizes and qualities of wicks, and also regulate the relative size of the tube and the wick, and in addition to this the length of the wick exposed in the container can be varied.

60 As above described, when oil is deposited on the wick, excess oil drops off readily, but a small quantity is constantly present and is carried along by capillary attraction until it emerges from the oil cup at the outlet 65 end of the outlet tube. This wick does not

completely block or obstruct the outlet tube as a fibrous wick would, and therefore during quiescent periods allows the ingress of air to the oil container through the outlet tube, so that there is no possibility of an air check causing a cessation of the flow of oil.

When the container is agitated and oil is deposited on the wick, sufficiently oil is drawn into the tube by wick capillarity, and by capillary action between the wick and the tube wall to establish syphonic action. On long continued action, however, if the supply of oil from the container is steady, there is a reduction of pressure established in the oil container, which temporarily prevents further feed until no more oil is supplied, that is, the container has come to rest, or until capillary feed from the tube to the bearing to be lubricated breaks the syphon, the turned over or syphon end, in the illustration this being the inlet end of the outlet tube, preventing any direct splashing into the outlet tube, and also cooperates with the wick to act as an oil filter to prevent foreign material passing down through the outlet tube and entering the bearing that is to be lubricated. In view of the non-supply of oil when the container is at rest there is a great economy of lubricant, since the feeding only takes place while the vehicle or other conveyance or machine element is in motion. This economy also has an advantage in that it necessitates only infrequent re-filling of the oil container.

It will be understood that minor changes can be made in the details of construction without departing from the scope of the invention.

I prefer to use the loosely wound wire 105 wick that is described herein, but it will be understood that under some conditions of use a tightly wound wick or a wick only partially filling the tube, or a woven wick, might be advantageously employed.

I claim:

1. An oil cup comprising a container, a restricted outlet tube with its inner end above the normal level of the oil in said container, the upper inner faces of the walls 115 of the container being disposed so that when the container is vibrated oil is splashed toward said inner end of the tube, and a wick of loosely wound wire strands in said tube.

2. An oil cup comprising a container, an outlet tube leading from the upper part of the inside of the container to the outside thereof, and a wick of loosely wound wire strands in said tube and projecting from the inner end thereof.

3. An oil cup comprising a container having a filling tube extending from the top part way into the container so that an air chamber is formed when the oil level reaches the bottom of the filling tube, a closure for 130

said filling tube, and an outlet tube extending to the outside of the container and having its open end in said air chamber.

4. An oil cup comprising a container having a filling tube extending from the top part way into the container so that an air chamber is formed around said tube when the oil level reaches the bottom of the tube, a closure for said filling tube, an outlet tube extending to the outside of the container and having its open end in said air chamber, and a wick of loosely gathered wire strands in said tube and extending beyond the inner end thereof.

5. An oil cup comprising a container with a filling tube extending inwardly from its top wall to form an air chamber when oil reaches the bottom of the filling tube, an outlet tube extending from the outside of the casing to the air chamber, said inner end being curved to open downwardly, and a wick of loosely arranged wire strands filling said tube and extending from the inner end thereof to form a loop.

In testimony that I claim the foregoing, I have hereto set my hand, this 18th day of August, 1920.

JEAN F. WOLFS.
